UNITED STATES PATENT OFFICE

2,411,967

DL-TOCOPHEROLS AND PROCESS FOR THE
MANUFACTURE OF SAME

Paul Karrer, Zurich, and Otto Isler, Basel, Switzerland, assignors to Hoffman-La Roche Inc., Nutley, N. J., a corporation of New Jersey

No Drawing. Application September 26, 1938,
Serial No. 231,846. In Switzerland March 31,
1938

23 Claims. (Cl. 260—333)

1

Evans and collaborators (Mem. Univ. California, vol. 8, year 1927) discovered that a nutritive factor which is indispensable for spermatogenesis in male rats and the successful completion of an existing pregnancy in female rats is contained in wheat germ oil and various foodstuffs. They named the new biological factor vitamin E and described a biological method of determination using female rats. Evans, Emerson and Emerson (J. Biol. Chem., vol. 113, year 1936, page 319, and vol. 122, year 1937, page 99) succeeded in isolating three distinct chemical substances from wheat germ oil and various other vegetable oils which are responsible for the vitamin E action of the starting materials. These closely related compounds were named α -, β - and γ -tocopherols. Investigations by Fernholz (J. Amer. Chem. Soc., vol. 59, year 1937, page 1154; vol. 60, year 1938, page 700), Karrer and collaborators (Helvetica Chimica Acta, vol. 20, year 1937, page 1422; vol. 21, year 1938, page 309), Bergel, Todd and collaborators (Biochem. J., vol. 31, year 1937, page 2257; J. Chem. Soc., year 1938, page 253), as well as John and collaborators (Zeitschrift für physiologische Chemie, vol 250, year 1937, page 11; vol. 252, year 1938, pages 201, 208) confirm and supplement the knowledge of the first named investigators regarding tocopherols.

α -Tocopherol was characterized by the empirical formula $C_{29}H_{50}O_2$, by an allophanate melting at 158° C., by a p-nitrophenylurethane melting at 131° C., and by a sublimate of durohydroquinone on thermal decomposition. β -Tocopherol possesses the empirical formula $C_{28}H_{48}O_2$, yields an allophanate melting at 143–144° C. and a sublimate of trimethylhydroquinone on thermal decomposition. An allophanate melting at 135° C. was produced from γ -tocopherol which has the empirical formula $C_{28}H_{48}O_2$.

It has now been found that by the action of trimethylhydroquinone or dimethylhydroquinone on phytol, phytolhalides, of 3-halogeno-dihydro-phytolhalides, suitably in presence of acid condensing agents, compounds can be obtained which contain a heterocyclic ring and which must be regarded as chromane derivatives of the general formula

wherein R is methyl or hydrogen.

2

The new compounds are the racemates with respect to carbon atom 2 of the chromane ring of tocopherols obtained from natural raw materials. They are light yellow, slightly viscous oils which, in the cold, gradually reduce alcoholic silver nitrate solution. On heating the reduction proceeds quickly. These oils dissolve in concentrated sulphuric acid with a yellow colour and the solutions fluoresce intensively after a few hours exposure to ultra violet light. The solution of the compounds in chloroform yields a deep dark brown colouration on the addition of tetranitromethane, which gradually clears up. On thermal decomposition the compounds form sublimes 15 of durohydroquinone or trimethylhydroquinone. When rats so far kept on a vitamin E-free diet were given these synthetic compounds it could be established that they enabled a litter of healthy young rats to be born exactly as did tocopherols 20 isolated from natural products.

The new compounds are to be used as pharmaceutical preparations or as starting materials for the manufacture of pharmaceutical preparations.

Example 1

25 1.7 parts by weight of trimethylhydroquinone are covered with 10 parts by weight of dry benzene (boiling point 80–100° C.). 1.0 part by weight of anhydrous zinc chloride and 4.8 parts by 30 weight of phytol bromide of the formula

35 prepared by the action of phosphorous tribromide on phytol, are added and the reaction product heated to 80° C. in a current of nitrogen for two hours. The product is then decomposed by 40 water, the benzene layer washed with dilute sodium hydroxide and water, dried, and, following this, a chromatogram prepared on aluminium oxide. The chromatogram consists of two layers: an upper layer which is grey, and a lower 45 layer which is light yellowish. The upper main layer is eluted by a mixture of methanol and ether and purified by the preparation of a sec-

ond chromatogram. The following condensation product is thereby obtained in a pure state:

The new compound from trimethylhydroquinone and phytol bromide contains 80.9 percent of carbon and 11.8 percent of hydrogen. The determination according to Zerewitinoff indicates the presence of one active hydrogen atom, i. e., a phenolic hydroxyl group. The compound possesses a characteristic absorption spectrum with a maximum absorption at $294\mu\mu$ and a minimum absorption at $256\mu\mu$. It forms various crystalline derivatives, such as a p-nitrophenyl-urethane melting at 131°C ., an allophanate melting at 172°C ., and a 3,5-dinitro benzoic ester melting at 63°C . On administering a dose of 5 mg to a rat kept on a vitamin E-free diet the full action of the pure vitamin was observed.

Example 2

4 parts by weight of trimethylhydroquinone are covered with 50 parts by weight of petroleum ether (boiling point $80-105^\circ\text{C}$). 3 parts by weight of anhydrous zinc chloride and 10 parts by weight of 3-bromo-dihydrophytyl bromide of the formula

prepared by the addition of hydrogen bromide to phytol bromide, are added and the reaction product heated in a current of nitrogen for 4 hours at a bath temperature of 140°C . The reaction product becomes brown with a vigorous evolution of hydrogen bromide. Finally, the product is treated with water, much petroleum ether added, the benzine layer thoroughly washed with Claisen's solution (a solution of 350 grams of potassium hydroxide in 250 grams of water and sufficient methyl alcohol to prepare one liter, see "Annalen der Chemie" vol. 418 [1919], page 96) and water, dried, adsorbed on aluminum oxide and developed with petroleum ether. The chromatogram shows an upper zone which is grey, and a lower zone which is light yellow. The product is eluted with a mixture of methyl alcohol and ether, the extract boiled in an atmosphere of nitrogen with 4 percent methyl-alcoholic potash in order to remove adhering bromine. For the preparation of the pure compound, another chromatogram is prepared from the product obtained by the extraction of the alkaline-aqueous methyl-alcoholic solution with ether.

The new compound is a yellowish oil. It yields a white, crystalline p-nitrophenylurethane melting at 131°C . (found N 4.69 percent, calculated 4.71 percent). If mixed with the p-nitrophenylurethane of α -tocopherol melting at 131°C ., the mixture melts without depression. A sublimate of durohydroquinone is formed on thermal decomposition.

Example 3

4 parts by weight of phytol, 2.5 parts by weight of trimethylhydroquinone and 1 part by weight of anhydrous zinc chloride are heated to 180°C . in a current of nitrogen for half an hour. The suspended matter gradually gives a homogeneous

brown solution whereby a little hydrogen chloride escapes and a small quantity of trimethylhydroquinone sublimes. The product is now cooled, precipitated with water, a lot of ether added, the ether solution washed with water, a solution of caustic soda, and water, dried and the solvent evaporated. The extract is dissolved in petroleum ether and adsorbed on an aluminium-oxide column. The chromatogram is developed with much petroleum ether. The upper uniformly grey zone contains the condensation product which has the same properties as the product obtained in accordance with Examples 1 and 2.

Example 4

4 parts by weight of phytol, 2.2 parts by weight of trimethylhydroquinone and 1 part by weight of anhydrous zinc chloride are suspended in 10 parts by weight of decalin and then heated to $150-160^\circ\text{C}$. for one hour while stirring and passing carbon dioxide. The trimethylhydroquinone dissolves completely, whereby the liquid becomes yellowish brown. The product is cooled, water and ether added with stirring, the ether solution washed successively with water, a solution of caustic soda, hydrochloric acid, and water, dried with sodium sulphate and the ether evaporated. The residue is adsorbed on an aluminium-oxide column. After development of the chromatogram with a good deal of petroleum ether, the column is uniformly grey. At the foot thereof there is a violet zone. The grey main zone is eluted with a mixture of methyl alcohol and ether (3:1), the solvent evaporated and the extract further purified by the preparation of a second chromatogram. The product is then distilled in a molecular distillation apparatus and the compound described in the previous examples obtained. This compound was given in doses of 3 and 10 mg. each to four rats which had been kept on a diet free from vitamin E. All the animals became pregnant and brought forth healthy young.

Example 5

11 parts by weight of phytol, 5 parts by weight of trimethylhydroquinone and 60 parts by weight of anhydrous formic acid are boiled together for 4-5 hours under reflux. The product is then diluted with water, extracted with ether, the ether evaporated and the residue saponified with an alcoholic solution of sodium ethylate or alcoholic potash. When the alcohol has been distilled off, the crude α -tocopherol is extracted from the alkaline mixture with ether. The ether solution is washed and dried. The solvent is then evaporated and the residue fractionated in high vacuum at a pressure of $10^{-3}-10^{-4}\text{ mm}$. A small preliminary fraction evaporating at $80-90^\circ\text{C}$. is separated; the principal quantity of the compound evaporates at $110-120^\circ\text{C}$. It is identical with the compound obtained in accordance with Examples 1-4.

Example 6

1 part by weight of 2,5-dimethylhydroquinone is heated on a boiling water-bath for three hours with 3 parts by weight of phytol bromide, 1 part by weight of anhydrous zinc chloride and 10 parts by weight of benzine boiling at $80-100^\circ\text{C}$. The reaction mixture is then decomposed by the addition of water, the benzine layer removed, washed, first with potash solution, then with water, and the solvent evaporated. The remaining residue is dissolved in a little low-boiling petroleum ether, filtered from a small quantity

for one hour while heating and introducing carbon dioxide. The m-xylohydroquinone dissolves completely. The fluid becomes yellowish-brown. The product is cooled, water and ether added while stirring, the ether solution washed with water, potash, hydrochloric acid and water, dried with sodium sulphate and the ether evaporated. The residue is adsorbed on an aluminium oxide column. After developing the chromatogram with much petroleum ether, the column appears almost uniformly yellowish-grey. At the bottom there is a small yellow zone. The yellowish-grey principal layer is eluted, the solvent evaporated and the residue purified by the preparation of a second chromatogram. The product is then distilled in a molecular distillation apparatus and the compound described in Example 9 is obtained.

Example 11

2.5 parts by weight of 3,5-dimethylhydroquinone, 4 parts by weight of 3-bromo-dihydrophytyl bromide and 1.5 parts by weight of anhydrous zinc chloride are dissolved in 20 parts by weight of petroleum ether (boiling point 80-105° C.) and then heated to 100° C. for two hours while stirring. The solution evolves a considerable quantity of hydrogen bromide and becomes brown. Finally, water and ether are added, the ether solution is then washed with potash and water, dried, and the solvent evaporated. The residue is dissolved in petroleum ether and adsorbed on an aluminium oxide column. After development of the chromatogram with petroleum ether it shows a nearly colourless principal zone and a yellow ring at the bottom. The principal zone is eluted with a mixture of methyl alcohol and ether, the extract boiled in an atmosphere of nitrogen with methyl alcoholic potash for the removal of adhering bromine. The alkaline aqueous methyl alcoholic solution is extracted with ether and another chromatogram prepared from the extraction-residue in order to obtain the pure compound which is of the same structure as the first product described in Example 8.

Example 12

2 parts by weight of 2,3-dimethylhydroquinone, 6.5 parts by weight of phytol bromide, 1.5 parts by weight of zinc chloride and 20 parts by weight of benzene are boiled for 4 hours under reflux. The working up of the reaction product is carried out as described in Example 7.

The preparation of a chromatogram of the product gives a narrow brownish layer in the upper part of the absorption column, then a yellow ring, and, at the foot thereof, a nearly colourless zone. The eluate of the brownish layer contains the expected condensation product of the following formula:

It is a viscous oil which has a strong reducing action. Its analysis corresponds with the formula $\text{C}_{22}\text{H}_{48}\text{O}_2$. The compound possesses an active hydrogen atom (calculated 0.24 per cent, found 0.24 per cent active hydrogen). When tested on rats which had been kept on a vitamin E-free diet, the compound proved fully active in a dose of 20 mg.

Example 13.

1.5 parts by weight of trimethylhydroquinone and 3.0 parts by weight of isophytol of the formula

are heated with 10 parts by weight of anhydrous formic acid for 6 hours. The mixture is diluted with water, extracted with ether, the ether layer washed with sodium hydroxide, then with water and the solvent evaporated. The condensation product remains as a viscous oil which readily reduces methyl-alcoholic silver nitrate solution. Its absorption spectrum has a maximum at $294\mu\mu$. The compound forms a crystalline allophanate of melting point 172-173° C. It is identical with dl- α -tocopherol.

We claim:

1. A synthetic tocopherol, which is racemic at the C atom in position 2 of the chromane ring, of the formula

wherein two of the R radicals represent a methyl group and the third R radical represents a radical selected from the group consisting of hydrogen and methyl radicals.

2. A synthetic tocopherol, which is racemic at the C atom in position 2 of the chromane ring, of the formula

3. A synthetic tocopherol, which is racemic at the C atom in position 2 of the chromane ring, of the formula

4. A synthetic tocopherol, the allophanate of which melts at about 172° C. and which is racemic at the C atom in position 2 of the chromane ring, of the formula

5. A synthetic, optically inactive tocopherol, of the formula

5

of solid matter and the solution poured through a column of aluminium oxide for the preparation of a chromatogram. The reaction product is rather firmly held by the adsorbent. The adsorption column is then divided into three parts and the separate parts eluted by a mixture of methanol and ether. The extract from the top zone possesses vitamin E activity. The active compound contained therein is of the following formula

From the second and third layers viscous oils are obtained after evaporation of the solvent which 20 do not possess vitamin E activity.

Example 7

1.5 parts by weight of 2,5-dimethylhydroquinone, 5.5 parts by weight of phytol bromide, 1.2 parts by weight of zinc chloride and 35 parts by volume of ligroin are boiled for 2 hours under a reflux condenser. The reaction mixture is then decomposed with water, the ligroin layer removed, washed with potash solution, then with water, and the solvent evaporated. The residue is dissolved in a small quantity of low-boiling petroleum ether and a chromatogram prepared on an aluminium oxide column. By eluting the yellowish-brown top zone with a mixture of ether and methanol, an oil is obtained which reduces a neutral methyl alcoholic solution of silver nitrate on boiling, and contains 0.2 per cent of active hydrogen according to the Zerewitinoff determination. These properties indicate that the oil isolated from the yellowish-brown upper zone is a compound of the following formula:

This compound possesses vitamin E activity and is the same compound as is obtained in Example 6.

From the lower part of the aluminium oxide column an oil can be eluted by means of a mixture of ether and methanol the analysis of which reveals that it has the formula C₄₈H₈₀O₂. The compound contains no active hydrogen (Zerewitinoff determination), and it does not reduce a methyl alcoholic solution of silver nitrate even on boiling. An allophanate cannot be prepared therefrom. This indicates that the compound does not contain a free hydroxyl group and that it probably has the following constitution:

Its absorption spectrum shows a maximum at 296 μμ and a minimum at 260 μμ.

6

Example 8

1.5 g. of 3,5-dimethylhydroquinone, 5 g. of phytol bromide, 1.2 g. of zinc chloride and 30 cc. of ligroin are boiled for 2 hours under reflux. The treatment of the reaction product is effected as described in Example 7. The preparation of a chromatogram on aluminium oxide gave at the top of the column a narrow, dark brown zone which is neglected, while the remainder of the column was of a light brownish colour. From the upper half of this part of the column an oil could be eluted which reduces a neutral solution of silver nitrate already on standing at room temperature; the reduction proceeds more quickly on heating. The analysis gave figures which show that the compound is of the following composition:

This compound possesses vitamin E activity. The oil obtained from the lowest part of the tube also reduces a solution of silver nitrate and an allophanate can be prepared therefrom which, 30 when analysed, gave figures which agree with the formula C₅₀H₈₂O₄N₂.

Consequently, the oil probably has the following constitution:

Example 9

4.5 parts by weight of phytol, 2.5 parts by weight of 3,5-dimethylhydroquinone and 1 part by weight of anhydrous zinc chloride are heated to 180° C. for 1/2 hour while stirring and introducing carbon dioxide. The suspended matter gradually fuses giving a homogeneous brown melt. After cooling, the product is treated with ether and water, the ether solution washed with potash and water, and the ether residue adsorbed on an aluminium oxide column. The chromatogram is developed with much petroleum ether. The whole of the lower part of the column is whitish-grey. The top layer of aluminium oxide, which is hardly coloured, is removed and the whitish-grey principal zone eluted with a mixture of methyl alcohol and ether (3:1). The solvent is evaporated in vacuo and the residue distilled in a molecular distillation apparatus. The compound is a yellow, slightly viscous oil, n_D²⁵=1.501, and is identical with the first product described in Example 8. A sublimate of trimethylhydroquinone results on thermal decomposition. An allophanate melting at 143° C. is obtained with cyanic acid in benzene solution. A 10 mg. dose of this compound was biologically fully active.

Example 10

4 parts by weight of phytol, 2.5 parts by weight of 3,5-dimethylhydroquinone and 1 part by weight of zinc chloride are suspended in 10 parts 75 by weight of decalin and then heated to 150° C.

copherol product, the steps of producing an α -tocopherol of the formula

which comprises condensing trimethylhydroquinone with an aliphatic di-terpene derivative of the formula

wherein R' represents one of the following radicals:

in the presence of zinc chloride, and recovering a tocopherol product from the reaction mixture thus obtained.

13. In a process for the manufacture of a tocopherol product, the steps of producing an α -tocopherol of the formula:

which comprises condensing trimethylhydroquinone with phytol halide of the formula

wherein Hal represents a halogen radical, under acid conditions, and recovering a tocopherol product from the reaction mixture thus obtained.

14. In a process for the manufacture of a tocopherol product, the steps of producing an α -tocopherol of the formula

which comprises condensing trimethylhydroquinone with phytol bromide of the formula

under acid conditions, and recovering a tocopherol product from the reaction mixture thus obtained.

15. In a process for the manufacture of a tocopherol product, the steps of producing an α -tocopherol of the formula

which comprises condensing trimethylhydroquinone with phytol bromide of the formula

in the presence of zinc chloride, and recovering a tocopherol product from the reaction mixture thus obtained.

16. In a process for the manufacture of a tocopherol product, the steps of producing tocopherol of the formula

which comprises condensing 3,5-dimethylhydroquinone with an aliphatic di-terpene derivative of the formula

wherein R' represents one of the following radicals:

under acid conditions, and recovering a tocopherol product from the reaction mixture thus obtained.

17. In a process for the manufacture of a tocopherol product, the steps of producing a tocopherol of the formula

which comprises condensing 3,5-dimethylhydroquinone with a phytol halide under acid conditions, and recovering a tocopherol product from the reaction mixture thus obtained.

18. In a process for the manufacture of a tocopherol product, the steps of producing a tocopherol of the formula

which comprises condensing 3,5-dimethyl hydroquinone with phytol bromide of the formula

under acid conditions, and recovering a tocopherol product from the reaction mixture thus obtained.

19. In a process for the manufacture of a tocopherol product, the steps of producing a tocopherol of the formula

13

which comprises condensing 3,5-dimethylhydroquinone with phytol bromide of the formula

$\text{CH}_3-\text{CH}-(\text{CH}_2)_3-\text{CH}-(\text{CH}_2)_3-\text{CH}-(\text{CH}_2)_3-\text{C}=\text{CH}-\text{CH}_2\text{Br}$

CH₃ CH₃ CH₃ CH₃

in the presence of zinc chloride, and recovering a tocopherol product from the reaction mixture thus obtained.

20. In a process for the manufacture of a tocopherol product, the steps of producing a tocopherol of the formula

which comprises condensing 2,5-dimethylhydroquinone with an aliphatic di-terpene derivative of the formula

wherein R' represents one of the following radicals:

under acid conditions, and recovering a tocopherol product from the reaction mixture thus obtained.

21. In a process for the manufacture of a tocopherol product, the steps of producing a tocopherol of the formula

which comprises condensing 2,5-dimethylhydroquinone with a phytol halide under acid conditions, and recovering a tocopherol product from the reaction mixture thus obtained.

5 22. In a process for the manufacture of a tocopherol product, the steps of producing a tocopherol of the formula

which comprises condensing 2,5-dimethylhydroquinone with phytol bromide of the formula

under acid conditions, and recovering a tocopherol product from the reaction mixture thus obtained.

23. In a process for the manufacture of a tocopherol product, the steps of producing a tocopherol of the formula

which comprises condensing 2,5-dimethylhydroquinone with phytol bromide of the formula

in the presence of zinc chloride, and recovering a tocopherol product from the reaction mixture thus obtained.
